UNITED STATES PATENT OFFICE.

GEORGE E. C. ROUSSEAU, OF OAKLAND, CALIFORNIA.

CONCENTRATOR.

Application filed September 9, 1921, Serial No. 499,440. Renewed September 4, 1924.

To all whom it may concern:

Be it known that I, GEORGE E. C. ROUSSEAU, a citizen of the United States, residing at Oakland, in the county of Alameda, State of California, have invented certain new and useful Improvements in Concentrators; and I do hereby declare the following to be a full, clear, and exact description of the invention, such as will enable others skilled in the art to which it appertains to make and use the same.

This invention relates to ore separators, and more especially to those working on wet stock and known as washers and the invention includes a grading or separating unit and two or more other units having shaking tables to which the separated grades of material are respectively delivered.

The broad object of the invention is to handle a stock mixture consisting of finely crushed mineralized rock and water, by subjecting it first to a separating process whereby the coarse gangue is removed and the remainder of the material is graded, and then subjecting the respective grades to further treatment for removing the fine gangue and collecting the concentrates in separate receptacles.

As hereinafter described and as has been found satisfactory, the first unit removes the coarse gangue and separates the remainder into only two grades, although it would obviously be possible to separate it more finely into a large number of grades and treat these individually. The following specification sets forth one successful embodiment of the invention, reference being had to the drawings wherein:

Figure 1 is a side elevation.

Figure 2 is a front elevation.

Figure 3 is an elevation of the back end of the machine.

Figure 4 is a vertical longitudinal section on the line 4—4 of Figure 2.

Figure 5 is a front elevation with the heads of the unit omitted.

Figure 6 is an enlarged vertical fragmentary view, showing the means of supporting the front end of revolving screens and drums in one of the three units.

Similar numbers refer to similar parts throughout the several views.

The water-tight and preferably cylindrical housing or casing 1 of the upper unit and the similar casings 2 and 3 of the two lower units are supported by an appropriate

framework 5 in such manner that the different positions of the units with respect to each other, will remain unchanged during their operation. The "stock" to be treated is admitted from a point above the machine through the hopper 60 and the stock feed 61. The latter by preference is a tube projected on an angle through the front head 11 and contains a spiral conveyor or worm 62 on a shaft 63 revolved at about 190 R. P. M., by means of the sprocket 64 fastened to shaft 63, chain 65, and sprocket 81, on the counter shaft 80.

Extending axially through the casing 1 is a shaft 10 carrying a sprocket 12 on its front end which sprocket, through chain 83, is connected with sprocket 82 on the counter shaft 80, and by this means gives the shaft 10 a speed of about 60 R. P. M. Mounted on this shaft is a tubular shaft 13 carrying a sprocket 14, and through chain 84, and sprocket 85 on the counter shaft 80, the said tubular shaft is given a speed of about 20 R. P. M. The solid shaft 10 carries heads or spiders 15 which support a tapered drum 16 open at front and rear ends formed from water proof material such as linoleum and having secured to its outer face a sheet iron casing to produce greater rigidity. The drum flares forwardly from its rear end and is supported at its forward end by the roller 90, mounted on pin 91, which pin is securely bolted to the front head 11. This is best seen in Figure 6. The tubular shaft 13 forwardly of the heads 15 carries heads or spiders 17 on which are supported two polygonal and by preference septilateral screens 18 and 19, the former or inner one being coarser than the latter and by preference having its walls in parallel relation to those of the latter as best seen in Figure 5. The rear ends of the screens 18 and 19 consist of wire mesh of the same fineness as screen 19, and the screens flare forwardly from their rear ends and gradually change from polygonal form at the rear ends to circular at the front ends where they are supported by rollers in the same manner as described for drum 16. To prevent the materials in the different screens from mixing with each other a circular ring 92, preferably of leather, is fastened to the head 11 as shown in Figures 4 and 6 thereby closing the space between the screens and head. The stock is delivered into the inner end of the coarser screen 18, the screens revolving about three

times as fast as drum 16. As opening 41 in the front head 11 forms an outlet for the coarse gangue from the inner screen 18 which passes through valve 42 to waste. 5 This valve is held in closed position by the spring 43 and through lever arm and roller 44, acted on by cam 45 attached to sprocket 14, is automatically opened once during each revolution of the tubular shaft 13. An 10 outlet 46 for second grade screenings leads from within the outer screen 19 through pipe 47 to a point above the shaking table 27 of the lower right hand unit. An outlet for first grade screenings leads from drum 16 15 and casing 1 through the pipe 48, and head 33 of the lower left hand unit, to a point above the shaking table 37 of this unit. The flow of first and second grade screenings is, as a result of this construction, continuous, but the discharge of coarse gangue is 20 intermittent. Water is admitted under pressure to the stock through the pipes 8 into both upper and lower units and is supposed to fill the screens, drums and casings and 25 from the latter it finds an overflow or escape through openings 51 of the upper unit and openings 52 and 53, of the lower units. Mounted on the rear end of shaft 10, and maintained in position thereon by means of 30 the collar piece 57 and springs 58, is a cam disk 54, the same being brought into contact with roller 55 which is secured to the rear end of casing 1. The rotation of this cam disk will impart to the shaft 10 a reciprocating or shaking motion which will be transmitted to the screens 18 and 19.

Through the center of the housing or casing 2, of the lower right hand unit, shown in Figure 5, is disposed a longitudinal shaft 40. 21, preferably having a sprocket 23 which, through chain 86 and sprocket on the counter shaft 80, is revolved at about 60 R. P. M., and on the heads or spiders 24, carried by this shaft, is mounted a tapered and open ended drum 26 formed from linoleum or 45 similar water tight material which has the external casing of sheet iron for obtaining the necessary rigidity. The front end of the drum is circular and is supported at this 50 end by the roller 90 as shown in Figure 6. This drum is spaced from the casing 2 so that the graded material is permitted to pass between the drum and casing. Forwardly of said spiders and within the drum 26, above its shaft 21, is disposed a table 27, which has the flanges 25 mounted on the 55 shaft and is engaged with the front head 22, so that it will assume an inclined position transversely of the drum, as shown in Figure 5, and in position to receive material through the discharge pipe 47. The table 27, between the flanges, consists of linoleum supported by sheet iron, and is given rigidity by the longitudinal rod 28 through and secured 60 to the flanges. Means are provided for im-

parting a reciprocatory motion to the table 27 and the drum 26, and this consists of a cam disk 72, roller 74, springs 78 and collar piece 77, operating in exactly the same manner as that described in connection with 70 upper unit. At the bottom and rear end of the casing 2 there is provided an outlet 120 for waste which discharges through the valve 121, said valve being operated into open position by the cam disk 72, which engages the lever arm 22, and into closed position by the spring 123.

As seen in Figure 2 the outlet pipe 48, for first grade screenings, is similarly led through the front head of the other lower 80 unit and deposited on top of the shaking table 37 of this unit, whose construction is identical with that of the first mentioned lower unit. The concentrates which find their way to the outlet 39 of this unit are of 85 course of different values from those in the concentrate outlet 29 of the right hand lower unit.

Stock material fed through the inlet 61 is delivered into the coarse polygonal screen 18 which removes and discharges the coarse gangue through the outlet pipe 41 and valve 42, the latter being opened once at each revolution of this screen, while at other times the presence of the gangue within the screen 90 tends, to some extent, to pulverize the material and to urge the finer material through the screen itself, it being understood that the casing 1 is nearly or quite filled with water and therefore the screen nearly or quite filled 95 with slime or stock while more is constantly fed thereto by the worm 62. The second grade material within the fine screen 19 is delivered through the pipe 47 to one lower unit, and the fine grade material within the 105 drum 16 is delivered through the pipe 48 to the other unit. The fine waste that has worked its way through the sides and back of the fine screen 19 is, by the pressure of the inflowing water, carried into the open 110 back end of drum 16 and passes through the outlet pipe 49, thence into the waste outlets of the lower units. The separated or graded material, in the lower units, is subjected to the actions of the reciprocating tables 27 115 and 37 and surplus gangue is carried to the rear and led out by means of the above described waste outlet while the heavier and valuable material is dropped from the table to the front end of drums 26 and 36 and 120 from there collected into the chambers or outlets 29 and 39.

What I claim is

1. In a concentrator, the combination with an upper unit having rotating screens for 125 removing the coarse gangue and grading the remaining material, means for feeding slime and water to this unit under a head of water pressure, and a water outlet having a control valve; of an outlet for the coarse 130

gangue and outlets for the respective grades, other lower units to which the last named outlets lead respectively, means therein for separating the values from the remaining material and collecting said values, in separate receptacles, and means for reciprocating the screens longitudinally.

2. In a concentrator, the combination with a unit comprising a fixed casing, a rotary shaft therethrough, screens carried by the shaft for removing the coarse gangue and grading the remaining material, a waste outlet for the coarse gangue, a valve therein, and cam mechanism on the shaft for opening said valve intermittently; of outlets from said casing for the respective grades, means on the unit for engagement with the cam to reciprocate the shaft and screens longitudinally.

20 3. In a concentrator, the combination with a fixed casing, a rotary shaft therethrough, a drum carried by the shaft, and a plurality of nested and placed screens also carried by the shaft within said drum; of means for feeding slime to the inner screen under pressure, a water outlet from said casing, manually operable means for controlling the same, an outlet for the coarse gangue to waste, a valve therein, cam mechanism on the shaft for opening said valve intermittently, constantly open outlets for the graded material, on the said casing, and means for engagement by said cam mechanism for reciprocating the shaft and associate drum and screens.

4. In a concentrator, the combination with a fixed casing, a substantially horizontal shaft having a reduced portion and a tubular shaft thereon, said shafts journaled in the casing and having means for removing them independently, an imperforate drum mounted on said solid shaft, and a plurality of nested and spaced screens of different mesh mounted on the tubular shaft within said drum; of means for feeding slime and water to the inner screen under pressure, a water outlet from said casing, manually operable means for controlling the same, a waste outlet for the coarse gangue, a valve therein, a cam on the shaft for opening said

valve intermittently, a projection on said fixed casing engaged with the cam, and resilient means for urging the cam into engagement with the projection, whereby the shaft and associated drum and screens will be reciprocated longitudinally.

5. In a concentrator, the combination with a fixed casing, a substantially horizontal shaft having a reduced portion and a tubular shaft thereon, said shafts journaled in the casing and having means for revolving them independently and at different speeds, an imperforate drum mounted on said tubular shaft and flaring toward the front head of the casing, a plurality of nested and spaced screens of different mesh mounted on the solid shaft within said drum and flaring to correspond with the flare of the drum, of an outlet for coarse gangue to waste opening through said front head at a low point within the coarse screen, a valve in said outlet, and a cam mechanism for intermittently opening the valve once at each revolution of said screen, and simultaneously reciprocating the shafts and associated drum and screens longitudinally.

6. In a concentrator, the combination with means for removing the coarse gangue and grading the remaining material under pressure, and outlets for the respective grades; of a unit for treating each grade, the same comprising a fixed casing into which said outlet leads, a shaft journaled therethrough and carrying a drum, a table having flanges loosely mounted on said shaft and under the delivery end of said outlet, a chute in which the values separated by the table collect, a pipe connected with said chute and leading to a receptacle, a waste outlet from said casing, a valve in the outlet, and cam mechanism on the shaft for opening said valve intermittently, and imparting longitudinal reciprocating motion to said shaft and the associated drum and table.

In testimony whereof, I affix my signature, in the presence of two witnesses.

GEORGE E. C. ROUSSEAU.
